to American Seating Company, Grand Rapids,
Mich., a corporation of New Jersey

Application November 18, 1938, Serial No. 241,091

3 Claims. (Cl. 155—184)

The present invention relates to chairs, particularly chairs for theatres and the like having backs with separate upholstery members; and its object is to provide in such a chair improved means for detachably mounting the upholstery member thereon.

This and any other and more specific objects hereinafter appearing are attained by, and the invention finds preferable embodiment in, the illustrative chair structure particularly described in the body of this specification and illustrated by the accompanying drawings, in which:

Figure 1 is an elevational rear view of a theatre chair;

Figure 2 is a vertical sectional view thereof (enlarged), taken on line 2—2 of Figure 1;

Figure 3 is a fragmentary rear view of lower portions of the chair's back;

Figure 4 is a fragmentary vertical sectional view thereof taken on line 2—2 of Figure 1;

Figure 5 is an elevational rear view of the upholstery member of the chair's back;

Figure 6 is a horizontal sectional view of the chair's back and standards taken on line 6—6 of Figures 1 and 2.

My improved means for detachably mounting on a chair an upholstery member of the back thereof is illustrated by these drawings in connection with a type of theatre chair to which said means is peculiarly well adapted.

The chair illustrated by these drawings has a seat 1 and a back designated generally 2 supported by and between the side standards 3. This back comprises the fixed rearward frame or body member 4 of sheet metal or the like having a rearwardly-bowed middle portion 5, forwardly extending lateral flanges 6 fastened as by rivets 7 on the inner sides of the standards and having also a downwardly open socket or recess 8 at its top formed by its overhanging forward flange 9, said back 2 comprising also the detachable forward upholstery member designated generally 10.

This upholstery member has a flexible front part, the sheet 11 of leather, fabric or the like, and a comparatively rigid rear part 12 of sheet metal or the like with stuffing 13 between these parts. The rear part 12 has a groove 14 in its rear side extending parallelly with its peripheral edge and formed by turning over its peripheral edge portion 15. These parts—the rigid part 12 and the flexible part 11—are securely held together by inserting the rod 16 into the groove 14 with the peripheral edge portion 17 of the flexible

sheet 11 clamped on the rod by said edge portion 15 of the rigid sheet, as best seen in Figure 4.

The upholstery member is detachably mounted on the chair by thrusting its upper end 18 into the recess or socket 8 and turning the screws 19, journaled at 20 in the rearwardly extending free ends 21 of the catches 22 which are pivoted at 23 on the rear side of the rigid part 12, so that said screws enter the threaded openings 24 in 10 the shelf 25 welded at 26 on the forward side of the fixed member 5, when the screws are turned the upholstery member is forced upwardly and its upper end is forced into its tightly seated position in said socket or recess as shown 15 in Figure 2. It will be seen that the flat inner sides of the heads of these screws bearing on the under side of the free ends 21 of the catches force the upholstery member upwardly when the screws are turned.

These catches are turnable to the position shown in broken lines in Figure 3 to permit insertion of the rod 16 and surrounding portion 17 of flexible sheet 11 into the groove 14 of the rigid part or sheet 12. When however these catches are turned to their operative position shown in Figures 1, 2, 4, 5 and 6 and in solid lines in Figure 3, they extend over the groove 14 and the rod 16 therein and securely hold the rod in place.

30 It will be seen that the upholstery member, although securely held in place by my holding means, may be readily detached for cleaning, repairing or replacement.

The invention being intended to be pointed 35 out in the claims, is not to be limited to or by details of construction of the particular embodiment thereof illustrated by the drawings or hereinbefore described.

I claim:

40 1. A chair back comprising: a rearward fixed member having a socket; a forward upholstery member movable along the fixed member into engagement in the socket, the upholstery member having a rigid rear part with a groove in its 45 rear side extending parallelly with its peripheral edge, a flexible front part and a rod inserted into the groove with the peripheral edge portion of said front part held in the groove by the rod; and means for detachably connecting said members in assembled position including a catch pivoted on the rear side of the upholstery member and turnable into and out of a position over the groove for holding the rod therein, and a screw journaled in the catch and in said position 50 thereof turnable in an internally threaded por-

tion of the fixed member for moving the upholstery member into and holding the same in the socket in the assembled position of said members.

2. A chair back comprising: a rearward fixed member having a socket; a forward member movable along the fixed member into held engagement in the socket, the forward member having a rigid part with a groove extending parallelly with its peripheral edge, a flexible part and a rod inserted into the groove with the peripheral edge portion of the flexible part held in the groove by the rod; means for detachably connecting said parts of the forward member in assembled position including a catch movably mounted on the rigid part movable into and out of a position over the groove and the rod therein for releasably holding the rod in the groove; and means for detachably connecting said members and moving the forward member into and

holding the same in the socket in the assembled position of said members, said last mentioned means including a screw journalled in one of said members and threaded in the other member.

5 3. A chair back comprising a rearward fixed member having a socket adjacent its upper periphery, a bracket secured to the forward surface of the fixed member having a forwardly extending flanged portion provided with a bolt 10 receiving aperture, a forward upholstery member movable relatively to the fixed member into engagement in the socket, and a screw threaded bolt screw threaded disposed within said aperture adapted to engage the forward member for 15 forcing the forward member into and detachably securing the same in said socket in assembled relation of the rearward and forward members.

ERVING B. MORGAN.
